US0D1042820S

(12) **United States Design Patent** (10) Patent No.: **US D1,042,820 S**
(45) Date of Patent: ** Sep. 17, 2024

(54) **PLUNGER**

(71) Applicant: **Medtronic, Inc.**, Minneapolis, MN (US)

(72) Inventors: **Matthew T. Vanderpool**, Minneapolis, MN (US); **Michael R. Klardie**, Bloomington, MN (US); **Kris A. Peterson**, St. Louis Park, MN (US)

(73) Assignee: **Medtronic, Inc.**, Minneapolis, MN (US)

(**) Term: **15 Years**

(21) Appl. No.: **29/748,588**

(22) Filed: **Aug. 31, 2020**

Related U.S. Application Data

(63) Continuation of application No. 15/610,076, filed on May 31, 2017, now Pat. No. 10,786,279, which is a continuation of application No. 14/204,227, filed on Mar. 11, 2014, now Pat. No. 11,311,312.
